UNITED STATES PATENT OFFICE.

DAVID S. JACOBUS, OF JERSEY CITY, AND NATHAN E. LEWIS, OF PLAINFIELD, NEW JERSEY, ASSIGNORS TO THE BABCOCK & WILCOX COMPANY, OF BAYONNE, NEW JERSEY, A CORPORATION OF NEW JERSEY.

FURNACE.

1,161,134.

Specification of Letters Patent.

Patented Nov. 23, 1915.

Application filed March 20, 1914. Serial No. 825,943.

To all whom it may concern:

Be it known that we, DAVID S. JACOBUS and NATHAN E. LEWIS, citizens of the United States, and residing at Jersey City, county of Hudson, and State of New Jersey, and Plainfield, county of Union, and State of New Jersey, respectively, have invented certain new and useful Improvements in Furnaces, of which the following is a specification.

Our invention relates to a furnace construction and more particularly to one used in connection with a Stirling boiler.

The features constituting the invention consist in the particular arrangement of the arches and to means for dividing the air for cooling the arches so as to admit a regulated amount above the lower or ignition arch of the stoker, and a regulated amount through a passage in the upper double arch, which arch directs the hot gases into the first bank of boiler tubes.

The invention will be understood by reference to the accompanying drawings in which—

Figure 1 is a longitudinal section of a furnace and boiler illustrating one embodiment and application of the invention, the stoker being shown in broken lines; Fig. 2 a section on the line 2—2 of Fig. 3, and Fig. 3 a front view of the air regulating damper.

Similar reference numerals indicate similar parts in the several views.

The invention is illustrated as applied to a standard Stirling boiler in which the tubes of the three banks 1, 2 and 3 are expanded into a water drum 4, the boiler being fired by a chain grate stoker 5 which may be of any approved type. Water boxes 6 extend longitudinally of the stoker and these are connected to the boiler circulation through pipes 7 and 8. The boiler parts are inclosed within the usual walls, the front wall comprising an outer metal casing 9.

The furnace chamber 10 is constructed with the usual ignition arch 11 which extends outwardly from the front wall of the setting. Above the inner end of the ignition arch is built a curtain wall 12, the arch 11 and wall 12 being spaced apart a sufficient distance to provide an air passage 13. Forming the roof of the main combustion chamber is a double arch extending in-

wardly from wall 12 nearly to the first bank 55 of tubes, said arch comprising sections 14 and 15 separated a sufficient distance to provide an air passage 16. The arches 11 and 14—15 are substantially parallel, the latter directing the hot gases into the first bank 60 of boiler tubes and into the secondary combustion chamber above the arch 14—15. The outer metal casing 9 is continued downward so as to inclose the front ends and side of arches 14 and 15 and wall 12, and the 65 exposed portion of arch 11, said casing being separated from the brick-work to provide a space for the admission of air through suitable openings therein. The space outside of the arches and curtain wall is closed at 70 its lower end by brick-work 11' and at its upper end by an angle plate 17. To divide or separate the air to be delivered through the passages 13 and 16 we introduce a seal 18, which may be asbestos packing, in the 75 space between the front of wall 12 and casing 9, and between the top of wall 12 and arch 14. The air to be delivered through the passages 13 and 16 is admitted to the space inside of casing 9 through openings 80 19 formed in said casing, and to regulate the amount of entering air we provide a damper 20 having openings corresponding to openings 19 and adapted to be moved between suitable guides to close the openings 85 19 more or less as may be desired. By this means the air is distributed evenly across the width of the setting.

In operation, with the dampers 20 open, the air from the outside enters the spaces 90 between casing 9 and the upper side of arch 11, and in front of the double arch 14—15, and in flowing through the passages 13 and 16 cools the arches.

In practice we have found that by employing the arrangement described the arches can be maintained under conditions where ordinary arches would fail. Practically the full furnace temperature is maintained by reason of the heating of the air in 100 passages 13 and 16, and complete combustion effected both in the main chamber 10 and the secondary combustion chamber above arch 14—15. The amount of air admitted is such that it does not interfere 105 with the economy of the boiler; in fact, there are beneficial effects through the minimizing of smoke.

What we claim and desire to secure by Letters Patent of the United States is:—

1. A boiler furnace having a fuel support, a curtain wall over the support, an ignition arch extending outwardly from the curtain wall over the fuel support, an upper arch extending inwardly from the curtain wall toward the boiler tubes, said upper arch having a passage for the admission of air 10 to the furnace chamber, an air passage being provided above the lower external arch and separated from the air passage for the upper arch, and each of the said air passages having its outlet to the combustion chamber at the rear end of its respective arch.
2. A boiler furnace having a fuel support, a curtain wall over the support, an ignition arch extending outwardly from the curtain wall over the fuel support, an upper arch extending inwardly from the curtain wall toward the boiler tubes, said upper arch having a passage for the admission of air 20 to the furnace chamber, an air passage being provided above the lower external arch and separated from the air passage for the upper arch, each of the said air passages having its outlet to the combustion chamber at the rear end of its respective arch, and 25 means for regulating the admission of air to said passages.
3. A boiler furnace having a fuel support,

a front wall therefor, an ignition arch extending outwardly from the front wall over the fuel support, an air inlet passage over 35 said outwardly extending arch, an upper arch extending inwardly from the front wall toward the boiler tubes, said upper arch being of double form with air ventilation between the two portions thereof, and 40 each of the said air passages having its outlet to the combustion chamber at the rear end of the arch.

4. A boiler furnace having a fuel support, a front wall therefor, an ignition arch extending outwardly from the front wall over the fuel support, an air inlet passage over 45 said outwardly extending arch, an upper arch extending inwardly from the front wall toward the boiler tubes, said upper arch being of double form with air ventilation between the two portions thereof, the air passages being separated from each other and 50 having means for independent regulation, and each having its outlet to the combustion 55 chamber at the rear end of the arch.

In testimony whereof we have hereunto signed our names in the presence of two subscribing witnesses.

DAVID S. JACOBUS.
NATHAN E. LEWIS.
